A technical cross-sectional diagram of a double-walled pipe. The outer wall has a thickness of 10 mm. The inner wall has a thickness of 5 mm. The gap between the two walls is 15 mm. The total width of the pipe is 23 mm. The diagram also shows a central longitudinal section with a width of 11 mm and a height of 10 mm. Various dimensions are labeled: 10, 5, 15, 23, 11, 10, 1, 8, and 20.

UNITED STATES PATENT OFFICE

FREDERICK K. FILDES, OF ALTOONA, PENNSYLVANIA

ATTACHMENT FOR CONTAINER CARRIERS

Application filed February 9, 1931. Serial No. 514,468.

This invention relates broadly to container carriers or means for the transportation of less-than-car-load freight such, for example, as the so-called container car service involving employment of enclosures which are carried either upon specially equipped railroad cars or motor trucks and trailers.

More specifically the present improvements have reference to an attachment for carriers adapted to the transportation of steel containers, which latter are individually assembled upon, and likewise are removable from, said carriers as and where required.

An important object of this invention is the provision of an attachment for flat carriers embodying support for less-than-capacity containers in spacial elevation relative thereto, said attachment including means to prevent both longitudinal, as well as lateral, shifting of the containers when deposited on the carrier and during transportation.

Another object is to provide an attachment of the kind referred to in which the means preventive of lateral shifting are moved into container-restraining position, by lowering of the container onto the carrier, and which gravitate or automatically recede from said container as it is initially elevated for removal.

A further object is to provide an attachment of the typified character that affords adequate clearance for the insertion of a lift truck below the individual containers and which affords no obstruction to easy removal of said containers from the carrier.

With the foregoing and other objects in view, as will be hereinafter apparent, this invention consists, in general, of certain novel details of construction and combinations of parts fully described herein, illustrated by the accompanying drawings, and specifically claimed.

In the drawings:

Fig. I is a part side elevation of a railroad flat car fitted with attachments in accordance with this invention.

Fig. II is an end elevation looking toward the left-hand of Fig. I.

Fig. III is a sectional view, drawn to a

larger scale, taken approximately as indicated by the arrows III—III in Fig. II.

Fig. IV is a fragmentary top plan view of one end of the attachment.

Fig. V is a perspective view of one of the lateral shift-restraining devices; and,

Fig. VI is a perspective view of a hanger or bearing member incorporated in the attachment.

Referring more in detail to the drawings, the numeral 1 designates, comprehensively, a portion of a railroad flat car, 2 the wheels, and 3 the supporting floor or platform thereof.

In accordance with this invention I dispose at intervals transversely across the car platform 3, a series of supports, comprehensively designated 4, and in view of the fact the several units are duplicates of one another, excepting the end ones 4', the following description is limited to an explanation of an individual support, in order to avoid repetitive matter.

Each support 4 comprises opposingly directed basal components, conveniently angled sections 5 of a length to extend across the full width of the platform 3 and attached thereto by appropriate securing means 6. These basal components 5 have rigidly fixed at their ends, as by rivets 7, U-shaped bearers or verticals 8; and, at intervals of their length, inverted U-shaped verticals 9, while said bearers or verticals jointly sustain the container supporting member 10 of the attachment 4.

The container supporting member 10 consists of a plate of suitable dimensions conveniently formed longitudinally to provide a medially-located barrier 11, with flanking horizontal portions 12, and downwardly angled flanges 13, whereby said supporting member is suitably secured to the verticals 8, 9, as by rivets 14, in a manner obvious to those acquainted with the art. Particular attention is here directed to the fact that the barriers 11 serve, as later on explained, to prevent longitudinal displacement of the containers 15 when on the flat car 3, and that the ends thereof are removed beyond the inter-

mediate U-shaped bearers 9 to accommodate the lateral shift-preventing means.

The lateral shift-preventing means conveniently comprises a bearing-hanger 16 of appropriate form to fit within the walls of the barrier 11 and be attached rigidly thereto by suitable securing means 17. Each bearing-hanger 16 affords medial support for a pivot pin or bolt 18 which also passes through spaced bearing bosses 19 fixed to the insides of the flanges 13, in any convenient manner, and as readily understood from Fig. IV, more particularly.

Mounted to each side of the bearing-hanger 16, on the pivot pin 18, is a hook or claw 20 of angular contour and I-cross-section with apertured embossments 21, proximate the heel portion 22 thereof, whereby such claws are pivoted to the pin 18 aforesaid, in an obvious manner.

The end attachments or supports 4' in most respects structurally conform with the foregoing description of the attachments 4, excepting that they are fashioned to provide only one horizontal 12 and accommodate but one hook or claw 20; and hence further explanation thereof is deemed unnecessary.

Having explained the structural features of the invention, it will be readily appreciated that as each container 15 is lowered into position, on the car 1, it will be guided by the ridge portions 23 of the barriers 11 between which it is to seat, onto the horizontal portions 12; and, incident to its approach thereto the container bottom will strike the hook heels 22 and rock them upwardly into the position shown to best advantage in Fig. II. Such movement of the hooks or claws 20 at each end of the attachments 4 or 4' swings the toe portions 24 into close approach with the walls 25 of the container 15 and thereby effectively prevents lateral or sidewise shifting of said container during transportation, whereas the stationary barriers 11 similarly restrain any tendency to longitudinal movement in an obvious manner.

Note is also to be had that the height or distance intervening the car floor or platform 3 and the bottom 26 of the container 15 and the top face of the attachment flanking horizontals 12, in practice about thirteen inches, affords clearance for easy insertion of a conventional lift-truck, whereby said container may be removed from the carrier or car 1 as and when required. Furthermore, it will be readily seen that when the container 15 is raised from below by a lift-truck, or by power actuated lifting tackle applied from above to the bails or links 27 at the top of said container, the hooks or claws 20 will fall down to the position indicated by dot-and-dash lines at the left hand of Fig. II, and as a consequence will offer no impedance to movement of the container 15 nor require said container to be raised more than a short

distance to clear the ridges 23 of the attachments 4 or 4'.

From the foregoing it will be understood this invention is susceptible of other adaptations, and embodiment in forms different from that which is illustrated by the accompanying drawings; hence I, therefore, consider as my own all such modifications thereof as fairly fall within the scope of the following claims.

Having thus described the invention, what I claim is:—

1. The combination with a container carrier of paralleling attachments affording elevated and longitudinal movement-preventing support for the container, and gravity-influenced movable means at the ends of such attachments effective to prevent lateral shifting of the container.

2. The combination with a container carrier of paralleling attachments affording elevated and longitudinal movement-preventing support for the container, and vertically swingable means at the ends of the attachments affording abutments preventive of lateral shifting, said movable means automatically receding below the container supporting level when said container is raised therefrom.

3. An attachment for flat carriers comprising basal components with stirrup verticals, a member attached to said verticals embodying a supporting surface with an upstanding barrier portion, and vertically swingable gravity-influenced members at the ends of said barrier portion.

4. An attachment for flat carriers comprising basal components connected together at their ends by substantially U-form verticals, similar inverted U-form verticals secured at intervals of the length of the attachment, a supporting member on said verticals embodying a barrier medially of its major dimension, and vertically swingable hooks at the ends of said barrier.

5. An attachment for flat carriers comprising basal components of standard sections connected at their ends by substantially U-form verticals of corresponding section, similar inverted U-form verticals rigidly secured at intervals between the first mentioned ones, a plate member mounted on the verticals and shaped to provide a medial barrier with flanking horizontal supporting portions and downwardly-directed attaching flanges, and vertically swingable hooks at the ends of said barrier.

6. An attachment for flat carriers comprising basal components of standard sections connected at their ends by substantially U-form verticals of corresponding section, similar inverted U-form verticals rigidly secured at intervals between the first mentioned ones, a plate member secured on the verticals and shaped to provide a medial hol.

low barrier with flanking horizontal supporting portions and downwardly-directed attaching flanges, bearing members secured in the ends of the hollow barrier, and vertically swingable angular hooks pivotally carried by the bearing members.

- 5 7. An attachment for flat carriers comprising basal components of standard sections connected at their ends by substantial 10 U-form verticals of corresponding section, similar inverted U-form verticals rigidly fixed at intervals between the first mentioned ones, a plate member securely mounted on the verticals and shaped to provide a 15 medial hollow barrier with flanking horizontal supporting portions and downwardly-directed attaching flanges, bearing members in the ends of the hollow barrier, and vertically swingable angular hooks pivoted proximate heel portions thereof to said bearing 20 members for opposed directional movement.

In testimony whereof, I have hereunto signed my name at Altoona, Pennsylvania, this 4th day of February, 1931.

DISCLAIMER

1,845,594.—*Frederick K. Fildes*, Altoona, Pa. ATTACHMENT FOR CONTAINER CARRIERS. Patent dated February 16, 1932. Disclaimer filed November 22, 1935, by the patentee.

Hereby enters this disclaimer to claim 1 of said patent, which is in the following words:

The combination with a container carrier of paralleling attachments affording elevated and longitudinal movement-preventing support for the container, and gravity-influenced movable means at the ends of such attachments effective to prevent lateral shifting of the container.

[*Official Gazette December 17, 1935.*]
